ATTORNEY

UNITED STATES PATENT OFFICE

LAWRENCE PURTELL, OF SALEM, MASSACHUSETTS, ASSIGNOR TO AMERICAN CAN COMPANY, OF NEW YORK, N. Y., A CORPORATION OF NEW JERSEY

CONTAINER

Application filed August 14, 1930. Serial No. 475,195.

The present invention relates in general to self-opening containers and is particularly adaptable as a preferred embodiment in a shoe polish box of the usual, general configuration.

The principal object of the invention is the provision of effective opening means easily secured to the container without impairing its sealing qualities.

10 Numerous other objects of the invention will be apparent as it is better understood from the following description, which, taken in connection with the accompanying drawing, discloses a preferred embodiment there-

15 of.

Referring to the drawing:

Figure 1 is a plan view of a container embodying the present invention with parts broken away;

20 Fig. 2 is a front elevation of the closed container parts being broken away;

Fig. 3 is a view similar to Fig. 2 illustrating the container in partially opened position; and

25 Fig. 4 is an enlarged sectional detail taken substantially along the line 4-4 in Fig. 2.

The container, as illustrated in the drawing, comprises a body 11 formed with a circumferential bead 12 protruding beyond the body wall, the portion of the body above the bead providing an external friction wall 13. Numeral 14 designates the cover member which is provided with a downwardly extending annular flange 15 adapted to frictionally engage the wall 13 of the body. The lower edge of the flange 15 rests against or is closely adjacent to the bead 12 when the container is closed.

30 The opening device comprises a lever 16 pivoted at 17 on a split rivet 18, the latter having spaced ends 19 which are driven through the wall of the flange 15 of the cover 14 and are then bent back or clinched on the inside wall of the cover, as illustrated at 21 in Fig. 4. The lever 16 is formed with a finger lug 22 and with a cam surface 23 (Figs. 2 and 3).

35 Opening of the container is obtained by movement of the lever 16, effected by a lifting action on its lug 22, this resulting in a par-

tial rotation about its pivot 17 during which time its cam surface 23 engages the bead 12 of the body (Fig. 3) and moves the cover up from the body thus prying these members apart.

40 The split construction of the rivet 18 makes it possible to dispense with all previously formed openings in the cover 14 which in the past have been a source of trouble in that variations between the rivet and such openings tended to impair the tightness of the closed container.

45 The improved type of rivet of the present invention, on the other hand, provides no path of air leakage, since the ends 19 are driven through the wall of the flange 15 forming their own openings, which operation is made possible by the solid construction of the rivet. The only metal of the wall that is disturbed in this action is the small 50 amount necessary to permit passage of the ends 19 of the rivet therethrough and the section of metal displaced is of the same size and shape as the rivet parts inserted therein. The clinching of the ends of the rivet which follows provides a further assurance against leakage and tightly closes all openings in the cover. This provides an improved type of 55 opener associated with a container which will retain the contents in much better condition by reason of the fact that air is not allowed to enter.

60 It is thought that the invention and many of its attendant advantages will be understood from the foregoing description, and it will be apparent that various changes may be made in the form, construction and arrangement of the parts without departing from the spirit and scope of the invention or sacrificing all of its material advantages, 65 the form hereinbefore described being merely a preferred embodiment thereof.

I claim:

70 A container of the usual thin sheet metal having a body member, a slip cover member 75 having a flange which frictionally engages around said body, an opening device pivoted on one of said members and arranged to be turned so as to bear against the other of said members to press them apart and open the 80

85 90 95 100

container, and a pivot for said opening device having a head, and a fixed bearing portion on which the opening device is rotatably mounted, and two ends spaced apart and extending from the margin of said bearing portion and extending through spaced perforations in the container member on which the opening device is pivoted and clinched on the inner face of the container member, whereby the pivot, with the opening device arranged on its bearing portion, may be applied to its container member by a driving and bending operation and secured at spaced places to the same.
